PHONOGRAPH RECORD HOLDER

Leonard F. Edmondson, Los Angeles, Calif.

Application July 21, 1955, Serial No. 37,065

Term of patent 14 years

(Cl. D33—10)

Fig. 1 is a perspective view of a phonograph record holder showing my new design;

Fig. 2 is a side elevational view as seen from the right side of Fig. 1;

Fig. 3 is a top plan view; and

Fig. 4 is a rear elevational view as seen from the right of the side elevational view shown in Fig. 2.

The phonograph records shown in broken lines in Fig. 1 are for illustrative purposes only.

I claim:

The ornamental design for a phonograph record holder, substantially as shown and described.
